Charles Schlayer

BY Frank J. Weyerth

ATTORNEY.

UNITED STATES PATENT OFFICE.

CHARLES SCHLAYER, OF NEW YORK, N. Y.

WRENCH.

1,277,490.

Specification of Letters Patent. Patented Sept. 3, 1918.

Application filed September 6, 1916. Serial No. 118,623.

To all whom it may concern:

Be it known that I, CHARLES SCHLAYER, a citizen of the United States, residing at the borough of Manhattan, city, county, and 5 State of New York, have invented certain new and useful Improvements in Wrenches, of which the following is a specification, reference being had therein to the accompanying drawings, which form a part thereof.

10 My invention relates to wrenches and more particularly to a wrench wherein the jaws may be positively and accurately set to any point of adjustment of a predetermined scale to adapt the wrench for use upon pipes 15 or nuts of different dimensions.

A wrench made in accordance with my invention is especially adapted to form part of the standard tool equipment for use in and about a particular mechanism, such as 20 an automobile, wherein the nuts or pipes used are standardized, the scale of adjustments of the wrench coinciding with the different nuts or pipes used in the mechanism. By providing for adjustments of the wrench 25 to secure only certain predetermined spacings of the jaws, stripping of the nuts and crushing or mutilation of pipes is prevented. The jaw construction of the wrench adapts it for use upon either hexagonal or square 30 nuts, and the jaws under all conditions of use engage four faces of a hexagonal nut and substantially the whole surface of opposite faces of a square nut, so as to avoid any possibility of slight play between the jaws and 35 the nut, resulting in such slippage as would result in stripping of the nut.

The wrench embodies a fixed jaw and a movable jaw which is movable toward and from the fixed jaw under the control of a 40 rotatable disk in setting the wrench, the arrangement and construction of these parts being such as to relieve the reciprocating jaw from excessive stresses, and have the greater stresses borne by the fixed jaw.

45 By pivotally mounting the movable jaw eccentrically of a rotatable disk, and by providing the fixed jaw with angularly arranged gripping areas and with a toothed portion extending at an angle to, and at one 50 side of, said gripping areas, the disk may be turned in a manner to space the effective gripping areas of the movable jaw, different predetermined distances from the said gripping areas without varying materially the 55 angular relation of the two jaws; or said disk may be moved in a manner to vary this

angular relation so as to bring the gripping areas of the movable jaw into the operative relation to the toothed portion, and to space the movable jaw different predetermined 60 distances from said toothed portion without materially varying the angular relation of the movable jaw and said toothed portion. The disk above referred to is used not only to secure the desired movements of the movable jaw, but also as a means for insuring the desired spacings of the jaws in setting the wrench, and locking the jaws, in any position in which they may be set. 65

By pivotally mounting the movable jaw 70 upon a rotatable disk, and providing the handle of the wrench with movable means for locking the disk with relation to the handle, or releasing said disk, this movable means may be located so as to be convenient 75 to the thumb when setting the jaw while allowing ample gripping capacity upon the handle to avoid accidental release of the disk when using the wrench.

The invention consists primarily in a 80 wrench embodying therein a handle, a fixed jaw thereon, the gripping area of which is presented away from the handle, a disk rotatably mounted in said handle, a jaw pivotally mounted eccentrically of said disk 85 and adapted to be positioned beyond the gripping area of said fixed jaw, and means whereby said disk may be locked in different positions; and in such other novel features of construction and combination of parts as 90 are hereinafter set forth and described and more particularly pointed out in the claims hereto appended.

Referring to the drawings:—

Figure 1 is a side elevation of a wrench 95 embodying my invention, the wrench being shown applied to a hexagonal nut;

Fig. 2 is a rear elevation thereof;

Fig. 3 is a side elevation of the head of the wrench applied to a pipe; and 100

Fig. 4 is a sectional view of the rotatable disk, the locking means therefor and the adjacent portions of the wrench.

Like letters refer to like parts throughout the several views.

In the embodiment of my invention shown in the drawings, *a* indicates the handle of an all metal wrench having a fixed jaw *b* at one end thereof having a gripping area or areas presented away from the handle. The gripping areas of the jaw *b* are angularly arranged, the angle of divergence of which is 105 110 115

approximately 120° so as to permit said jaw to engage adjoining sides of a hexagonal nut, while at the same time permitting the wrench to be used with square or other polygonal nuts.

Mounted upon the handle *a* adjacent the fixed jaw *b* and adapted to be positioned beyond the gripping area thereof is a movable jaw *c* also having angularly arranged gripping areas, with substantially the same degree of divergence as the areas of the jaw *b*. To adapt the wrench for use upon pipes or other cylindrical bodies, I form the gripping areas of the jaw *c* of a plurality of teeth or serrations, such as are ordinarily used in pipe wrenches.

The movable jaw *c* is pivotally mounted eccentrically of a disk *d* rotatably mounted in a circular opening *d'* in an enlarged or swelled portion *a'* of the handle *a*, the shank *c'* of the jaw *c* being bifurcated so as to straddle the jaw *b* and handle *a*, and thus hold the disk *d* against lateral displacement. The pivot *e* passes through both arms of the shank *c'* and the disk *d*. The periphery of the disk *d* has a sequence of stops thereabout, the spacing of these stops determining the different dimensions for which the jaws may be set for use upon either a nut or a pipe. The handle *a* is provided with means coöperating with said stops whereby the disk *d* and the movable jaw *c* may be locked in any set position.

In the form of the invention shown in the drawings, the stops above referred to consist of two series of sockets *f*—*f'*, the former of which are used in securing adjustment of the jaw *c* for different sizes of nuts, and the latter in securing such adjustment for pipes of different diameters. The coöperating locking means comprises a pin *g* slidably mounted in the handle *a* and having a close fit with the several sockets of the series *f* and *f'*, said pin being pointed to secure sufficient wedging action to facilitate accurate setting of said disk *d* and its jaw *c*. The pin *g* is carried by a spring pressed trigger *h* mounted in lugs upon the handle *a*, the enlarged outer end thereof being loosely mounted in said trigger in order to compensate for the arc described by said trigger as it moves in either direction, by means of the keeper plate *h'*. The spring acting on said trigger is indicated at *h''*.

The jaw *b* adjacent its gripping areas as indicated at *b'* is of greater breadth than the handle *a*, being of substantially the same breadth as the jaw *c* so that when the wrench is used upon a nut, the shank *c'* will engage the edges of the portion *b'* of the jaw *b* in a manner to relieve the pivot *e* from excessive stresses irrespective of the dimension for which the said jaw *c* is set, since a substantially parallel movement of said jaw is secured by reason of the simultaneous ro-

tary movement of said disk *d* and of the jaw *c* about the pivot *e*.

Extending at an angle from one edge of the jaw *b* is a serrated or toothed gripping surface *i*, this surface being spaced away from the axis of the disk *d* sufficiently to cause the positioning of the disk *d* to permit the engagement of the pin *g* with any of the sockets *f'* to bring the jaw *c* into the proper relation to said surface *i* to secure the desired gripping and ratchet action with relation to a pipe, or other similar object.

When the wrench is to be used upon or about an automobile, I provide the end of the handle *a* with a narrow, circular extension *j* to be used as a key in opening and closing gas tanks. This construction is highly effective since the jaw *c* may be swung laterally of the handle *a* in a manner to permit it to be used as a lever handle by means of which screw caps, or valves, may be set hard, or readily opened irrespective of their condition. The key *j* is designed to be used in lieu of a coin.

The operation of the herein described wrench is substantially as follows:—

When it is desired to use the wrench upon a nut, the jaw *c* is turned about the pivot *e* until it comes to rest upon the edges of the extended portion *b'* of the jaw *b*. The trigger *h* is then depressed, disengaging the pin *g* from one of its coöperating sockets *f* or *f'* and permitting the disk *d* to be turned in either direction. By merely pulling the jaw *c* outwardly of the handle *a*, or pushing it toward said handle, the disk *d* will be caused to turn, thus varying the spacing between the jaws *b* and *c*, the jaw *c* having a substantially rectilineal movement by reason of the simultaneous rotary movements of the disk *d* and the jaw about the pivot *e*.

When the jaw *c* has been set as desired, the trigger *h* is released and the pin *g* will enter one of the sockets *f* and prevent further rotary movement of the disk *d* in either direction.

The jaws may either be set upon the nut, or may be slipped over the nut after being set. If the wrench be used upon a hexagonal nut, the angularity of the jaws *b* and *c*, as to their gripping areas, will result in the simultaneous engagement of four faces of the nut, and hence slight play between the wrench and the nut cannot cause the stresses to be applied to the corners of the latter in a manner to permit sufficient slippage to cause stripping of said corners. This angularity of the jaws also results in the greater stresses being applied by the fixed jaw, in a manner to relieve the pivot of the movable jaw from excessive shearing strains, the engagement of said jaw with the shoulders upon the edges of the portion *b'* assisting in preventing the transmission of such excessive stresses to said pivot.

When it is desired to use the wrench as a pipe wrench, the trigger *h* is actuated to release the disk *d* and the jaw *c* is swung outwardly from the handle *a*, so as to bring 5 the gripping areas into the desired relation to the surface *i*. In setting the wrench to a given diameter, the disk is turned so as to bring some one of the series *f'* of the sockets where it can be engaged by the pin *g*, thus 10 insuring the proper angular relation of the jaw *c* to the handle *a* and surface *i*. By swinging the jaw *c* away from the jaw *b* and surface *i*, said jaw may be readily slipped over the pipe or other circular object, which may thereafter be brought 15 toward the surface *i*, with said jaw *c* to secure the desired clamping action. This movement of the jaw *c* toward and away from the surface *i*, also secures the desired 20 ratchet-like action of the wrench for securing succeeding bites upon the object.

In setting the wrench to a pipe or other circular object of a given diameter, the trigger *h* is released when the jaw *c* has been 25 set thus causing the pin *g* to enter one of the sockets *f'* and prevent further rotary movement of the disk *d* as when setting the jaw *c* for a given size of nut.

It will be observed that a wrench made in 30 accordance with my invention can be set to secure only certain predetermined spacings of the jaws as determined by the spacings of the sockets of each series *f* or *f'* with relation to each other, and that the arrangement and formation of the jaws is such as 35 to compensate for any slight play between them and the object to which they are applied.

In the drawings, I have shown a wrench 40 especially adapted for use upon hexagonal nuts, but it is apparent that it may be used effectively upon square or other polygonal nuts, although if desired the angle of the jaws may be varied to adapt the wrench to 45 different shapes of nuts. It is also apparent that the operative range of different wrenches may be varied or that an increased range of any wrench may be secured by increasing the diameter of the disk *d* as 50 compared with the showing of the drawings.

The manner of using the key *j* is apparent from the foregoing description.

While it is desirable to embody in a single structure those features which adapt the 55 wrench for use upon both nuts and pipes or other circular objects, nevertheless it is apparent that a wrench adapted for use upon either nuts, or pipes or other circular objects may be made by the mere omission 60 of those structural characteristics of the fixed jaw which adapt it for engagement with nuts or the omission of the surface *i* and a corresponding modification of the disk *d*.

65 It is also to be observed that when the

pivot *e* is axially aligned with the handle *a*, the jaw *c* may be used with either the jaw *b* or the surface *i*, whether the pivot *e* be at the point closest to the jaw *b* or at the point most remote from said jaw. 70

It is not my intention to limit the invention to the details of construction shown in the accompanying drawings, it being apparent that such details may be varied without departing from the spirit and scope of the 75 invention.

Having described the invention what I claim as new and desire to have protected by Letters Patent is:—

1. A wrench embodying therein a handle, 80 a fixed jaw thereon, the gripping area of which is presented away from the handle, a disk rotatably mounted in said handle, a movable jaw pivotally mounted eccentrically of said disk and adapted to be positioned 85 beyond the gripping area of said fixed jaw, and means whereby said disk may be locked in different positions.

2. A wrench embodying therein a handle, 90 a fixed jaw thereon, the gripping area of which is presented away from the handle, a serrated or toothed surface carried by said handle and projecting at an angle from one edge of said jaw, a disk rotatably mounted in said handle, a movable jaw pivotally mounted eccentrically of said disk, and adapted to be positioned beyond the gripping area of said fixed jaw, and means whereby the angular relation of said movable jaw and said handle may be varied and 95 said disk may be locked in different positions. 100

3. A wrench embodying therein a handle, 105 a fixed jaw having angularly diverging areas thereon, the gripping area of which is presented away from the handle, a disk rotatably mounted in said handle, a movable jaw having angularly diverging gripping areas pivotally mounted eccentrically of said disk, and adapted to be positioned beyond the 110 gripping area of said fixed jaw, and means whereby said disk may be locked in different positions.

4. A wrench embodying therein a handle, 115 a fixed jaw having angularly diverging gripping areas presented away from said handle, a serrated or toothed surface carried by said handle and projecting at an angle from one edge of said jaw, a disk rotatably mounted in said handle, a removable jaw having angularly diverging, serrated or toothed gripping areas pivotally mounted eccentrically of said disk adapted to be positioned beyond the gripping areas of said fixed jaw, and means whereby the angular 120 relation of said movable jaw and said handle may be varied and said disk may be locked in different positions. 125

5. A wrench embodying therein a handle, 130 a fixed jaw thereon, the gripping area of

which is presented away from the handle, a disk having a sequence of sockets about the periphery thereof, rotatably mounted in said handle, a movable jaw pivotally mounted eccentrically of said disk, and adapted to be positioned beyond the gripping area of said fixed jaw, a pin mounted in said handle adjacent said disk and adapted to enter said sockets respectively to lock said disk in different positions, and means whereby said pin may be withdrawn from or projected into said sockets.

6. A wrench embodying therein a handle, a fixed jaw having angularly diverging gripping areas presented away from said handle, a disk having a sequence of sockets about the periphery thereof, rotatably mounted in said handle, a movable jaw having angularly diverging gripping areas pivotally mounted eccentrically of said disk and adapted to be positioned beyond the gripping areas of said fixed jaw, a pin mounted in said handle adjacent said disk and adapted to enter said sockets respectively to lock said disk in different positions, and means whereby said pin may be withdrawn from or projected into said sockets.

7. A wrench embodying therein a handle, a fixed jaw thereon, the gripping area of which is presented away from the handle, a disk having a sequence of sockets about the periphery thereof, rotatably mounted in said handle, a movable jaw pivotally mounted eccentrically of said disk and adapted to be positioned beyond the gripping area of said fixed jaw, a pin mounted in said handle adjacent said disk and adapted to enter said sockets respectively to lock said disk in different positions, and a spring actuated trigger mechanism, said pin being loosely mounted in said trigger mechanism.

8. A wrench embodying therein a handle, a fixed jaw having angularly diverging gripping areas presented away from said handle, a disk having a sequence of sockets about the periphery thereof, rotatably mounted in said handle, a movable jaw having angularly diverging gripping areas pivotally mounted eccentrically of said disk and adapted to be positioned beyond the gripping areas of said fixed jaw, a pin

mounted in said handle adjacent said disk and adapted to enter said sockets respectively to lock said disk in different positions, and a spring actuated trigger mechanism, said pin being loosely mounted in said trigger mechanism.

9. A wrench embodying therein a handle, a fixed jaw thereon, the gripping area of which is presented away from the handle, a serrated or toothed surface carried by said handle and projecting at an angle from one edge of said jaw, a movable jaw adapted to be positioned beyond the gripping area of said fixed jaw, a support for said movable jaw movable substantially axially of said handle and transversely thereto, whereby said movable jaw may be spaced different distances from said fixed jaw or said surface and brought either into the operative relation to said fixed jaw or to said toothed or serrated surface, a pivotal connection between said movable jaw and said support and means whereby said support may be locked in different positions.

10. A wrench embodying therein a handle, a fixed jaw thereon, the gripping area of which is presented away from the handle, said jaw being broader than said handle whereby shoulders are formed at one side of said jaw, said handle having a circular opening therethrough, a disk rotatably mounted in said opening, a movable jaw having a bifurcated shank straddling said handle and said disk, and adapted to be positioned beyond the gripping area of said fixed jaw, a pivot passing through said shank and said disk eccentrically thereof whereby said movable jaw may be moved substantially rectilinearly with the rotation of said disk with its shank in substantially continuous engagement with said shoulders, and means whereby said disk may be locked in different positions.

In witness whereof, I have hereunto affixed my signature this 31st day of August, 1916, in the presence of two subscribing witnesses.

CHARLES SCHLAYER.
